(57) CLAIM

The ornamental design for a tool holder, as shown and described.

DESCRIPTION

FIG. 1 is a perspective view of a first embodiment showing the back side of a tool holder incorporating my ornamental design;

FIG. 2 is a perspective view the front side of the tool holder of FIG. 1 incorporating my ornamental design;

FIG. 3 is a plan view the back side of the tool holder of FIG. 1 incorporating my ornamental design;

FIG. 4 is a plan view the back side of the tool holder of FIG. 1 incorporating my ornamental design;

FIG. 5 is a plan view the front side of the tool holder of FIG. 1 incorporating my ornamental design;

FIG. 6 is a plan view the left side of the tool holder of FIG. 1 incorporating my ornamental design;

FIG. 7 is a plan view the right side of the tool holder of FIG. 1 incorporating my ornamental design;

FIG. 8 is a plan view the top side of the tool holder of FIG. 1 incorporating my ornamental design;

FIG. 9 is a perspective view of a second embodiment showing the back side of a tool holder incorporating my ornamental design;

FIG. 10 is a perspective view the front side of the tool holder of FIG. 9 incorporating my ornamental design;

FIG. 11 is a plan view the back side of the tool holder of FIG. 9 incorporating my ornamental design;

FIG. 12 is a plan view the front side of the tool holder of FIG. 9 incorporating my ornamental design;

FIG. 13 is a plan view the left side of the tool holder of FIG. 9 incorporating my ornamental design;

FIG. 14 is a plan view the right side of the tool holder of FIG. 9 incorporating my ornamental design; and,

FIG. 15 is a plan view the top side of the tool holder of FIG. 9 incorporating my ornamental design.

The features shown in broken lines in the drawings depict environment of the tool holder that form no part of the
